UNITED STATES PATENT OFFICE.

ALEXANDER FERDINAND VICTOR, OF DAVENPORT, IOWA.

DESIGN FOR A PICTURE-DISPLAY CABINET.

Application filed December 15, 1924. Serial No. 11,701. Term of patent 3½ years.

To all whom it may concern:

Be it known that I, ALEXANDER FERDINAND VICTOR, a citizen of the United States, residing at Davenport, in county of Scott and State of Iowa, have invented a new, original, and ornamental Design for a Picture-Display Cabinet, of which the following is a specification, reference being had to the accompanying drawing, forming part hereof.

Fig. 1 is a vertical front elevation of the structure showing my design.

Fig. 2 is a vertical side elevation thereof.

Fig. 3 is a top plan view of my picture display cabinet.

I claim:—

The ornamental design for a picture display cabinet as shown.

Signed at Davenport, in the county of Scott and State of Iowa, this 28th day of Oct. 1924.

ALEXANDER FERDINAND VICTOR.
